CLAIM

I claim the ornamental design for a cover for an end of a butter stick, as shown and described.

DESCRIPTION

FIG. 1 is a front perspective view of a cover for an end of a butter stick, showing my new design;

FIG. 2 is a rear perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof; and,

FIG. 7 is a bottom plan view thereof.

The broken lines showing text in FIGS. 1, 3 and 4 depict environmental matter and form no part of the claimed design.
